UNITED STATES PATENT OFFICE

JACOB COHEN, OF MIDDLE VILLAGE, NEW YORK

DESIGN FOR A HAND BAG

Application filed September 7, 1926. Serial No. 18,995. Term of patent 3½ years.

To all whom it may concern:

Be it known that JACOB COHEN, a citizen of the United States, and resident of Middle Village, in the county of Queens and State of New York, has invented a new, original, and ornamental Design for Hand Bags, of which the following is a specification, reference being had to the accompanying drawing, forming part thereof, in which—

Fig. 1 is a front elevational view of a hand bag embodying my new design; and

Fig. 2 is an end elevational view thereof.

I claim:

The ornamental design for a hand bag as shown.

Dated New York city, September 3, 1926.

JACOB COHEN.
